FEEL MEANS FOR PRESSURE FLUID
FOLLOW-UP SERVOMOTOR

Charles Reginald Churn, Tilehurst, England, assignor to The Fairey Aviation Company Limited, Hayes, England

Application February 18, 1947, Serial No. 729,286
In Great Britain January 24, 1946

5 Claims. (Cl. 121—41)

1

It is known that balanced manually-operated ailerons on an aircraft produce, on the pilot's control, an effort varying in magnitude with the speed of the aircraft and which, by resisting the pilot's effort, gives him a sense of "feel" of which he is robbed if the ailerons are power-operated. The object of the present invention is to restore this sense of "feel" by inducing a reaction proportional to the total actuating effort required, and although it will be described with reference to the power actuation of aircraft control surfaces, it is not restricted thereto, and may be employed in the power actuation of any other control surfaces where a similar sense of "feel" is desirable, for instance, on the rudder of a boat.

To this end and in accordance with the present invention hydraulic servo means for actuating a control surface comprise a jack cylinder, a jack piston connected with the control surface to be actuated, a selector valve for the jack and a reaction piston within the jack piston, the pilot's control being connected directly with the selector valve and through a lost motion device with the reaction piston, the arrangement being such that the fluid pressure admitted to the jack acts also, in the opposite direction, against the reaction piston to produce a sense of "feel" at the pilot's control.

The jack piston may be formed with internal stops to limit the travel of the reaction piston relatively to said jack piston, so as to provide direct manual control if the hydraulic pressure fails.

Alternatively, the reaction piston may be formed with an external and an internal stop near the point where it merges from the jack piston to coact with said jack piston and thus limit the travel of the reaction piston relatively to said jack piston, so as to provide direct manual control if the hydraulic pressure fails.

In another alternative, the jack cylinder instead of being directly secured, e. g. to the aircraft, may be slidably mounted in an anchorage and normally locked relatively thereto under the action of the hydraulic pressure, but may be releasable therefrom if the hydraulic pressure fails, and may be permitted to move axially relatively to said anchorage to provide direct manual control if the hydraulic pressure fails.

The jack cylinder may be formed with a circumferential groove and the anchorage may be provided with a collet arranged to be movable radially inwards by a piston to engage said groove and so anchor the jack cylinder under the influence of the hydraulic pressure acting on the

2

piston, but, if the hydraulic pressure fails, to be movable radially outwards out of the groove under spring pressure, so releasing the jack body relatively to the anchorage.

Four forms of the invention as applied to aircraft will be described with reference to the accompanying drawings in which:

Figure 1 is a diagrammatic sectional elevation of one form,

Figure 2 is a fragmentary sectional elevation of a modified construction,

Figure 3 is a diagrammatic sectional elevation of another form,

Figure 4 is a similar view of yet another form,

Figure 5 is a diagrammatic end elevation of the form shown in Figure 4,

Figure 6 is a fragmentary cross-section on the line VI—VI, Figure 5, showing components in the normal position during operation of the servo,

Figure 7 is a fragmentary cross-section on the line VII—VII, Figure 5, showing further components in the normal position during operation of the servo,

Figure 8 is a fragmentary view similar to Figure 6, showing the components in the emergency position, and

Figure 9 is a fragmentary view similar to Figure 7, showing the corresponding components in the emergency position.

Referring to Figure 1 of the drawings, a jack body 10 anchored to the aircraft at points 11 contains a jack piston 12 having two hollow stems 13, 14 extending axially on either side of it, of which

14 is connected by a rod 15 with the control surface 15^a to be actuated, and termed the actuating stem, the other, 13, being free, and termed the free stem. The hollow stems 13, 14 are pierced radially at 16, 17 respectively to provide fluid communication between their interiors 18, 19 and the corresponding chambers 20, 21 of the jack cylinder 10.

Within the jack piston 12 and the stems 13, 14 is a reaction piston 22 which passes slidably through the jack piston 12, and is sealed at 23 and 24. This reaction piston 22 extends axially along the stems, and with them forms two chambers 18, 19, which are separated from one another at the point where the reaction piston 22 passes through the jack piston 12, but which are in fluid communication respectively with the two chambers 20 and 21 of the jack cylinder 10.

The reaction piston 22 is further formed with two lands 25, 26 at a point just before it emerges from the open end 27 of the free stem 13, thereby sealing the chamber 18 within the free stem and

also forming a gallery 28 between the lands 25, 26. There are therefore three chambers formed by the jack piston 12 and its stems 13, 14 and the reaction piston 22, namely, a chamber 19 within the actuating stem 14, in fluid communication through the passages 17 with the jack chamber 21 around it; a chamber 18 within the free stem 13, in fluid communication through the passages 16 with the other jack chamber 20, which is around it; and a gallery 28 within the free stem 13 at its free end, and bounded by lands 25, 26 on the reaction piston 22. Further, the reaction piston 22 has an axial passageway 29 and ports 30, 31 at the ends thereof serving to establish fluid communication between the gallery 28 and the chamber 19 within the actuating stem.

Mounted on and near the free end 27 of the free stem 13 is a selector valve 32 comprising a valve operating rod 33, and body 34, an inlet port 35 in communication with the hydraulic pressure pipeline of the aircraft, an outlet port 35^a in communication with the return pipeline, and two ports 36, 37 in communication respectively with the gallery 28 and with the chamber 18 in the free stem 13. The valve rod 33 of the selector valve 32 is connected directly with the pilot's control 38. A link 39 in the connection, consisting of a sleeve slidably mounted on the free end 42 so as to be kept in alignment therewith, is slotted as at 40, and engages with a pin 41 carried by the free end 42 of the reaction piston 22, thus forming a lost-motion device connecting the pilot's control 38 with the reaction piston 22. Slot 40 may have a notch 40^a in its side for a purpose to be described presently.

There are therefore two alternative fluid paths for the hydraulic pressure, namely, through the first port 36 of the selector valve 32 to the gallery 28 in the free stem 13, and thence via the axial passageway 29 in the reaction piston 22, the chamber 19, and the passage 17 to the jack chamber 21 around the actuating stem 14; or through the second port 37 of the selector valve 32 to the chamber 18 in the free stem 13, and thence, through the passage 16, to the jack chamber 20.

In operation, initial movement of the pilot's control 38 moves the valve rod 33 and places one or other of the selector valve ports 36, 37 in communication with the hydraulic pressure inlet 35. This admits fluid pressure to one of the chambers 18, 19, in the jack piston 12 and to the corresponding jack chamber, driving the jack piston 12 in the direction selected, and driving the reaction piston 22 in the opposite direction. This movement of the reaction piston 22 takes up the remaining lost motion between the pin 41 and slot 40 and is then felt by the pilot, who must resist it to keep the valve 32 open.

The efforts exerted by the servo and the pilot are in the ratio of the cross-sectional areas of the jack chamber 20 or 21 and the reaction piston chamber 18 or 19, and may be predetermined to any desired value by the arrangement of suitable dimensions of the bores.

When the pilot's control member 38 is initially displaced, say to the left in Figure 1, the valve rod 33 is also moved in the same manner via 39, but the valve-carrying member 13 and pin 41 are not moved. Thus, initially, only the valve rod 33 moves, such movement bringing the pin 41 to the end of the slot 40, when the valve will only be just open. Further movement of the control 38 will open the valve fully and also displace the reaction piston 42-22 which is endeavoring to travel in the opposite direction, under the influ-

ence of the pressure which has been admitted into annular chamber 19 by the initial valve opening. The same pressure is also operative in chamber 21 of the jack and causes member 14 to travel in the same direction as that selected by member 38 and valve 32. At the instant that movement of member 38 is stopped, and with it 39 and 33, the pressure is still being fed into chamber 21, causing 14 to continue its movement. As the valve body 34 is rigidly attached to 14 via 13 and 12, the valve body must move relatively to the stationary valve rod 33, thereby closing the valve port originally selected open.

The pin 41 will remain at the end of the slot 40 until the valve is selected in the opposite sense, when it will move to the other end of slot.

If desired, the lost motion between pin 41 and slot 40 can be dispensed with, e. g. by a slight rotation of stem 42 so that pin 41 on piston 22 engages recess 40^a at the side of slot 40. The provision of this slot and pin connection obviates the necessity for moving the reaction piston 42-22 when operating valve rod 33, and permits valve operating loads to be much smaller than would otherwise be the case. In case of pressure failure, leaving only manual effort available, the pin and slot can be locked together by engaging notch 40^a with the pin, thus reducing the lost motion in the control.

Figure 2 shows a modification of the construction illustrated in Figure 1. The body of the jack piston 12, having a smaller internal diameter than that of the actuating stem 14, is employed as a stop to limit the axial travel of the reaction piston 22 relatively to the jack piston, and a further stop 14^a, consisting of an inwardly directed flange 14^a integral with the actuating stem 14, is provided to restrict the axial travel of the reaction piston 22 away from the jack piston 12.

In the event of failure of the hydraulic pressure, a control run is thus provided between the pilot's control and the control surface to be actuated, it being understood that in addition to the lost motion between the pin 41 and slot 40 there is also lost motion to be taken up between the reaction piston 22 and one or other of the stops, after which there is direct manual control.

If desired, the lost motion between the pin 41 and slot 40 can be dispensed with, in the same manner as explained above with respect to Fig. 1.

Referring to an alternative embodiment shown in Figure 3, the reaction piston chamber is formed at the free end of the free stem 13, and is sealed from the interior 43 of the jack piston 12 by an internal flange 44 through which passes a stem 45 attached to one side of the reaction piston 22. The selector valve 32 controls two fluid paths, one of which connects the hydraulic pressure line 46 with the reaction piston chamber 47, and also, by means of a flexible pipe connection 49, with the jack chamber 21. The fluid return line 51 is then connected with the reaction piston chamber 48 and, by the flexible pipe connection 50, with the jack chamber 20. The other fluid path joins the hydraulic pressure line 46 with the other reaction piston chamber 48 and by means of the flexible pipe connection 50, with the jack chamber 20, corresponding return connections being made with the return line 51. The stem 52 of the reaction piston is formed with two stop rings 53, 54, the former within the reaction piston chamber 47 and the latter outside it, and there is a seal 55, at the point where the end of the reaction piston emerges from the chamber

47, which acts as an abutment causing the stop rings 53, 54 to limit the axial travel of the reaction piston 22. The amount of travel permitted is sufficient for normal operation of the servo, but if the hydraulic pressure fails, the pilot can operate the control surface manually since, after he has taken up the lost motion due to the axial travel of the reaction piston 22, further movement of the control column 38 is transmitted by one of the stop rings 53, 54 to the free stem 13 of the jack piston, and thence by the rod 15 to the control surface.

Figures 4 to 9 show yet another form of the invention, in which the jack body 10, instead of being permanently anchored to the aircraft, is slidably mounted in an anchorage 56 so as to be capable of axial movement therein. The anchorage 56 is formed with a chamber 57 (see Figures 6 and 7) containing a locking piston 58 capable of axial movement against a compression spring 59 when fluid pressure is admitted through a passage 60 at one end of the chamber 57. The jack body 10 is formed with an annular depression or groove 61 at its middle.

Passing radially through the chamber 57 of the jack anchorage 56 is the stem 62 of a cut off valve 63 of the piston type, the stem being held in a valve body 64 and pressed radially inwards against the jack body 10 by a compression spring 65, the inner end of the cut off valve terminating in a roller 66 to minimize friction when the jack body 10 moves axially. The valve body 64 and stem 62 are bored to present an unobstructed passage for fluid pressure when the roller 66 is in the annular depression 61 of the jack body 10, that is, when the jack body is centrally disposed relatively to the anchorage 56, but when the jack body is out of the central position, the roller 66 is lifted out of the annular depression 61 and the stem 62 is raised, thus obstructing the passage. One side of the cut off valve 63 is connected with the hydraulic pressure line 46, and the other side with the passage 60 admitting pressure to one end of the chamber 57 of the jack anchorage 56.

Within the jack anchorage 56 and rigidly attached thereto is a collet 67 embracing the jack body 10 and having an axial slot to accommodate and allow relative movement of the cut off valve roller 66. The collet 67 has two resilient blades terminating in jaws 68 which tend to spring radially outwards, but which can be forced inwards, by ramps 69 on the inner wall of the locking piston 58, to engage in the annular depression 61 in the jack body 10.

In normal operation the jack body 10 is centrally disposed in the anchorage 56, and therefore the cut off valve roller 66 is in the annular depression 61 and the cut off valve is open, as shown in Figure 6. Fluid pressure is hence admitted through the passage 60 to the jack anchorage chamber 57, and forces the locking piston 58 against its compression spring 59 and the ramps 69 on its inner wall against the collet jaws 68, locking them in engagement with the annular depression 61 in the jack body 10, as shown in Figure 7. The jack body 10 is thus kept locked to the jack anchorage 56 and the servo operates in the manner previously described.

Should the hydraulic pressure fail, however, the locking piston 58, under the force of its compression spring 59, expels the fluid from the jack anchorage chamber 57 and allows the collet jaws 68 to spring outwards and hence unlock the jack body 10 from the jack anchorage 56, as shown

in Figure 9. The entire servo mechanism is therefore now slidable within the jack anchorage, and may be used by the pilot in an emergency as an ordinary link in the control run. When the jack body 10 is moved from the normal central position it raises the roller 66 out of the annular depression 61 and closes the cut off valve as shown in Figure 8, thus isolating the locking piston 58.

The cut off valve may alternatively be of the poppet type.

The advantages of the systems of Figures 4 to 9 are as follows:

(1) They provide a safeguard against valve or jack seizures (from any cause) when used in conjunction with pressure systems where the pressure feed to the valve can be turned "off" and released at operator's will. Thus in case of seizure, when the operator finds he is unable to move the control, he turns the pressure off and thus releases the mechanism from its anchorage in the axial sense. The control can then be moved manually as a whole.

(2) They provide a means for use in lightly powered controls where assistance is required under one set of conditions, such as, maximum maneuverability at high speeds, and where assistance is not required (on some aircraft) as when landing and during other low-speed flying.

In such applications the pressure could be switched "on" or "off" at operator's will.

I claim:

1. In an arrangement for actuating a control surface, hydraulic servo means comprising a jack cylinder, a jack piston within said cylinder, connecting means between said jack piston and said control surface, a reaction piston within cylinder means formed in said jack piston, a source of fluid pressure, a selector valve arranged to control the admission of fluid pressure to said jack cylinder, a pilot's control connected directly with said selector valve, a lost motion device connecting said pilot's control and reaction piston and permitting limited relative axial movement in each direction between said control and said reaction piston, and means admitting said fluid pressure into the cylinder means to act on said reaction piston simultaneously with, but in a contrary direction to, the admission of fluid pressure to said jack piston, so causing the reaction piston to produce a sense of "feel" at said pilot's control.

2. In an arrangement for actuating a control surface, hydraulic servo means as claimed in claim 1, the jack piston having internal stops limiting the travel of the reaction piston relatively to the jack piston, so providing a direct connection between the pilot's control and the control surface to be actuated if the fluid pressure fails.

3. In an arrangement for actuating a control surface, hydraulic servo means as claimed in claim 1, the reaction piston being formed with an external and an internal stop, near the point where it emerges from the jack piston, limiting the travel of the reaction piston relatively to the jack piston, so providing a direct connection between the pilot's control and the control surface to be actuated if the fluid pressure fails.

4. In an arrangement for actuating a control surface, hydraulic servo means comprising a jack cylinder anchorage, a jack cylinder slidably mounted within said anchorage, a source of fluid pressure, means actuated by said fluid pressure and adapted to lock the jack cylinder relatively to the anchorage, a jack piston within said jack

cylinder, connecting means between said jack piston and said control surface, a reaction piston within cylinder means formed in said jack piston, a selector valve arranged to control the admission of fluid pressure to said jack cylinder, a pilot's control connected directly with said selector valve, a lost motion device connecting said pilot's control and reaction piston and permitting limited relative axial movement in each direction between said control and said reaction piston, and means admitting said fluid pressure into the cylinder means to act on said reaction piston simultaneously with, but in a contrary direction to, the admission of fluid pressure to said jack piston, so causing the reaction piston to produce a sense of "feel" at said pilot's control so long as the fluid pressure is operative, but, when said fluid pressure fails, the locking means freeing the jack cylinder relatively to the anchorage and causing a direct connection between the pilot's control and the control surface to be established.

5
10
20

5. In an arrangement for actuating a control surface, hydraulic servo means as claimed in claim 4, the jack cylinder being formed with a circumferential groove and the anchorage being provided with a collet and a piston arranged to move said collet, under the influence of the hydraulic pressure, into said groove and so anchor the jack cylinder.
